CLAIM

The ornamental design for a combined container and applicator for hair tint, as shown and described.

DESCRIPTION

FIG. 1 is an isometric view including the rear end of a combined container and applicator for hair tint showing my new design;

FIG. 2 is an isometric view including the front end;
FIG. 3 is an isometric view showing the inside of the cap; and

FIG. 4 is an isometric view of a disc to be placed inside the cap to prevent any dispensing.
